CHRYSLER CORPORATION, A CORPORATION OF DELAWARE

PROCESS OF GRINDING TOOTHED ARTICLES

Application filed March 7, 1923. Serial No. 623,328.

This invention relates to a process of grinding a toothed article and to the article so ground.

It often is desirable to grind certain segments of toothed articles such as splined shafts and the like, so that only certain segments thereof shall be ground while other segments are left in the milled or other relatively unfinished condition. For example, in the 10 case of a splined shaft it may be desirable only to grind the valley portions, that is, the cylindrical portion between the splines. Various expedients for grinding such internal surfaces have been tried. In the so-called form- 15 grinding, a grinding wheel is provided whose face is formed complementary to the entire segment to be ground and the entire face of such segment is finished in one pass of the wheel longitudinally of this segment, and 20 before the succeeding segment is operated upon. Another method is the so-called generative grinding in which the face of the wheel is not complementary to or coextensive with the segment to be ground, but the wheel 25 is moved over the segment to develop the desired shape. Both these methods as heretofore carried out have certain objections.

The principal object of the present invention is to provide an improved method for 30 grinding certain portions of a toothed article.

The invention is illustrated and described in this application as applied to the grinding of the valley segments between the splines of a splined shaft. The invention, however, 35 is not limited to this particular operation, but may be employed in the grinding of other toothed articles and may be applied to the grinding of other portions of such articles.

In the present application there is illustrated and described a method of generative grinding which may be utilized to act successively upon the successive curved segments to be ground and gradually develop the desired shape of the article, and, if desired, without 40 necessitating the finishing of an entire segment before a successive segment is operated upon. The Thomas Patent No. 1,252,509 sets forth a method of generative grinding, but various objections to it will be evident to 45 those skilled in the art. By the present in-

vention these objections are overcome. For the purpose of illustration and not as a limitation, the method will be described as carried out for the grinding of the cylindrical valley portions only of a shaft provided with integral splines. 55

In the drawings, which are merely illustrative of the method, Fig. 1 is a side elevation of a splined shaft in contact with the grinding wheel shown broken away in side 60 elevation;

Figs. 2, 3 and 4 are details;

Fig. 5 is a perspective view of a grinding wheel which may be used; and

Figs. 6 and 7 illustrate a modified construction which may be used. 65

1 indicates the shaft provided with splines 2 to 5 between which are curved segments desired to be ground, such as the valley portion or segment 6. Relief grooves, such as 7 at the 70 base of the splines may be provided if desired. The shaft is suitably mounted and held so that it may be positively rotated at any desired speed, and, in the case of an article such as a long shaft, so that it may be simultaneously moved longitudinally of its axis as indicated by the arrow at the right in Fig. 1. The grinding wheel 8 is provided and mounted to rotate on a transverse axis, that is, on an axis transverse, and preferably at substantially 75 a right angle, to the axis of the shaft. It is driven by suitable mechanism not shown. The grinding face which contacts with the valley portion 6 is preferably flat, as indicated at 9 in Fig. 2. It contacts tangentially 80 with the curved surface 6 as it touches the surface only at substantially one point, see Figs. 1 and 2.

It will be obvious that if the shaft is then rotated in the direction of the arrow and the grinding wheel is also rotated, the grinding face will travel relatively over the surface 6 and grind it to the shape desired. But some provision for allowing the grinding wheel to 85 skip the advancing spline or allow the latter to pass must be provided. This may be accomplished, without moving either the shaft or the grinding wheel bodily away from the other, by shaping the grinding wheel with a 90 cut-away portion such as will allow the suc- 95

cessive splines to pass without interference. In the present embodiment this is illustrated by forming the grinding wheel 8 as indicated in perspective in Fig. 5, in which the face of the grinding wheel is provided with a helical groove 10 which will allow the successive splines to pass without in this case touching the splines at any point, if desired. The pitch of the helical face is such that with a given angular speed of the shaft, the valleys may be ground without touching the splines, as will be obvious.

Referring, for example, to Fig. 2, the grinding wheel has just engaged the leading edge 15 of the surface 6. When the shaft has rotated to the position shown in Fig. 3, the shaft has rolled relatively over the grinding face 9 which has then moved relatively toward the left, as indicated. When the shaft has rotated to the position indicated in Fig. 4, the grinding face has moved relatively further to the left, due to the pitch of the helical groove, thus allowing the spline or tooth 2 to enter the groove 10. As the shaft and wheel 25 continue to revolve, the spline will move in this groove until it clears the same, as indicated by the spline 3 in Fig. 3. A similar segment 12 will then engage the face of the grinding wheel and the operation will be repeated on this successive segment. The other valley segments 13 and 14 will similarly be ground.

It will be observed that in this operation it is unnecessary to move bodily either the shaft 35 or the grinding wheel away from the other. They retain their relative bodily positions at all times.

In order that the wheel may contact with the shaft throughout its length, the one should 40 be moved relatively to the other axially of the shaft. It is preferable to move the shaft bodily and longitudinally of its axis during the grinding operation. By so positively rotating both the shaft and the grinding wheel 45 and slowly moving the shaft axially of itself, the contact point between the wheel and shaft is caused to travel over the valley portions in a helix or spiral of very low pitch. By making the grinding wheel of relatively 50 large diameter compared with that of the shaft, the curve of the wheel at the point of contact is quite gradual and consequently the wheel makes grinding contact with the shaft in a relatively broad line, and if the shaft is 55 moved axially quite slowly, the surface will be generated quite smooth and of great accuracy.

It will be obvious that the grinding wheel, 60 where it contacts with the shaft, moves longitudinally of the shaft and consequently the lines of abrasive are longitudinal of the shaft. Such lines are difficult to reproduce in drawing but are indicated by 15 in Fig. 1. The 65 helical line of abrasive contact between the wheel and shaft is indicated at 16, although it

must of course be understood that such helical line is only faintly distinguishable upon the ground shaft itself when a wheel of relatively large diameter is used. A grinding wheel substantially one foot in diameter operating upon a splined shaft about one and one-eighth 70 inches in diameter across valley portions has been successful. The pitch of the helical groove in the grinding wheel which should be used will of course depend upon the angular speed of rotation of the splined shaft. These 75 may easily be worked out by any mechanic.

Figs. 6 and 7 show a modification which 80 may be used. In this a grinding wheel 17 having a cylindrical and non-helical face is shown with a portion 18 cut away to clear the splines, as indicated by the spline 19. The remainder of the wheel, such as 20, is of such diameter as will contact with the valley portion. When the shaft and grinding wheel are rotated at the proper relative angular 85 speeds, the cut-away portion 18 will allow the spline to pass and the remainder of the wheel to grind the curved valley portion as will be obvious.

Various advantages of this method of grinding will be obvious to those skilled in the art, and it will be evident that the method herein disclosed obviates many of the objections to prior known methods.

It is recognized that this method is susceptible of utilization in a variety of ways and for the grinding of various surfaces on different forms of toothed articles. The claims are therefore not limited to the particular steps or embodiments which have been above set forth merely as illustrative examples.

What I claim is:

1. The process of grinding splined shafts, 105 which comprises positively rotating a splined shaft with its valley portion in contact with the helically formed peripheral grinding face of a rotating grinding wheel arranged with its axis transverse to the axis of the 110 shaft, and in timed relation to the rotation of the wheel to cause the helix to enter successively between the splines of the shaft to 115 grind the valleys and simultaneously moving relatively the shaft and wheel longitudinally of the axis of the shaft.

2. The process of grinding spline shafts, 120 which consists in subjecting a splined and hardened shaft to the action of an abrasive hob having its grinding surface formed as a helix, with its axis transverse to that of the shaft, and rotating the said shaft directly as distinct from by the worm action of the helical grinding surface to present different surfaces in succession to the abrasive hob with 125 each rotation of the latter.

3. The process of grinding spline shafts, 130 which consists in subjecting a splined and hardened shaft to the action of an abrasive hob having its grinding surface formed as a

helix with its axis transverse to that of the shaft, rotating the said shaft directly as distinct from by the worm action of the helical grinding surface to present different surfaces in succession to the abrasive hob with each rotation of the latter, and advancing the shaft toward the hob during the correcting operation.

4. The process of grinding toothed articles having series of teeth arranged in an arc, which comprises placing the article in grinding contact with a grinding wheel having a peripheral portion thereof cut away to allow the teeth to pass, and arranged with its axis transverse to the axis of the article, moving relatively the grinding wheel and article to transfer the point of contact in the general direction of the axis of said arc, and turning relatively the article and wheel substantially about the axis of said arc other than by the contact of the wheel with the article and in timed relation to the rotation of the wheel to carry the teeth of the article successively through the cutaway portion of the wheel.

25 5. The process of grinding toothed articles having a circular series of teeth, which comprises placing the article in grinding contact with a grinding wheel having a peripheral portion thereof cut away to allow the teeth to pass, and arranged with its axis transverse to the axis of the article, moving the article to transfer the point of contact in the direction of the axis of the article, and turning the article about the axis thereof other than by the contact of the wheel with the article, and in timed relation to the rotation of the wheel to carry the teeth of the article successively through the cutaway portion of the grinding wheel.

40 6. The process of grinding a toothed shaft or the like which comprises bringing the valley portions of a toothed shaft or the like into tangential contact with a grinding wheel having a peripheral portion thereof formed with a helical groove to allow the teeth to pass, and arranged with its axis transverse to the axis of the shaft, rotating the shaft about its axis other than by the contact of the wheel with the shaft and in timed relation to the rotation of the wheel to cause the teeth of the shaft to pass successively through the grooved portion of the wheel and moving the shaft longitudinally during the grinding operation to cause the wheel to grind the valley portions of the shaft successively in helical paths.

Signed at Detroit, Michigan, this 2nd day of March, 1923.

FRED J. LAMBORN.
